METHOD OF AND APPARATUS FOR COATING
PAPER

Donald R. Macdonald, Leominster, Mass.

Application September 15, 1936, Serial No. 100,925

8 Claims. (Cl. 91—59)

This invention relates to an improvement in the method and apparatus for effecting an even distribution of coating materials to webs or sheets of paper or like materials.

The application of coating materials is usually accomplished by applying the desired material to a traveling ribbon, web or sheet of material by spraying the material onto the sheet, by immersing the sheet in a bath of the material, or by bringing the sheet into contact with a roll or other device to which the coating material has been applied. The coating material thus applied is smoothed out to a uniform thickness, and the excess material removed by scrapers, brushes, air jets or other suitable mechanism.

My invention deals with an improved method of and apparatus for effecting a more even distribution of this coating film on the traveling web, and deals more particularly with the improvement in the apparatus which employs a jet of air for the above purpose.

In the manufacture of coated paper it is very necessary that the coating materials be distributed uniformly over the entire width and length of the sheet or web in order that subsequent operations on this sheet or web may be satisfactorily performed and a high grade of paper having a uniformly smooth and polished surface be obtained. If the coating material is not deposited in the proper amount or of the proper thickness, or is deposited unevenly or of thicker composition on some portions of the sheet than others such irregularities cause subsequent operating and manufacturing difficulties, and greatly reduce the quality of the sheet finally produced.

One of the most satisfactory means found to effect an even distribution of the coating materials over a traveling web of paper is to impinge a narrow jet of compressed air (or other gas) on and against the sheet after the coating material has been applied. This jet of air (or gas) being directed uniformly over the entire width of the traveling web or sheet. The impact of the air on the freshly coated sheet accomplishes three necessary objectives. First it forces the coating materials against the sheet effecting a more intimate bond and contact therewith; second, it effects an even distribution of the coating materials over the width and length of the sheet by leveling off the thick or high portions and filling in on those sections which initially did not have a sufficient thickness or amount of coating applied; and third, it removes any surplus or unnecessary coating material from the sheet effect-

ing economy in cost and insuring a uniform product.

While my invention is hereinafter described as dealing particularly with the application of coating materials to a traveling web or sheet of paper, and an improvement on the methods of and apparatus for distributing these coating materials uniformly over the web or sheet by a jet of air, still this description shall not be interpreted as limiting my invention to the application of coating materials exclusively to paper, or the application of my improvements exclusively to distributing means utilizing air jets.

My invention is illustrated by the following drawings—

Fig. 1 is a diagrammatic representation of a coating machine showing the point at which my improved device is applied.

Fig. 2 shows a front view of a portion of such machine.

Fig. 3 is an enlarged sectional view of a portion of Fig. 1 showing a particular application of my device to an air distributing nozzle or jet.

Fig. 4 shows an enlarged view of a portion of Fig. 2.

Fig. 5 shows an enlarged view through one of the air adjusting valves.

Fig. 6 shows a modification of my device as applied to an air distributing nozzle and is optional with the device shown in Fig. 3.

In my preferred form of device the sheet or web of paper or other material is taken from a roll 1 over one or more guide rolls 2 and then over a coating roll 3 which roll is immersed in a bath of coating mixture contained in tank 4.

The coating mixture in tank 4 is in fluid form and a coating or layer adheres to the surface roll 3. This surface comes in contact with the under side of the traveling web or sheet and leaves on the surface of the sheet a quantity of coating material more or less uniformly distributed over its entire width.

After leaving roll 3 the uncoated side of the sheet passes around roll 5 being drawn or moved along by means of a porous belt 6 traveling over a suction box 7 and driven by means of rolls 8. The suction box 7 holds the sheet or web tightly against the porous belt 6 and results in sufficient friction between the paper web and the belt to draw the paper along with the belt over the various coating and guiding rolls previously referred to from the storage roll 1.

Adjacent to roll 5 is mounted a compartment or box 9 of suitable size and shape extending the entire width of the machine and of the traveling

web. One side or corner of this box is provided with a narrow groove or slot 10 located adjacent to the roll 5. Compressed air or other gas is supplied through pipe 11 to the interior of box 9 and the box and slot 10 are so located that this air or gas pressure will impinge on the surface of the traveling web passing over roll 5. This web is designated as 1w.

The box 9 is mounted in a manner so that it can be moved into suitable position and location relative to roll 5 and the traveling web 1w and can also be swung or moved out of position when necessary for examination or any other reason. The mechanism for accomplishing this purpose is not shown.

The mechanism heretofore described deals with a conventional method of applying a coating material to a traveling web of paper and illustrates particularly as before mentioned the air jet type of device for distributing this coating uniformly over the surface of web 1w and of removing any excess, surplus or unnecessary material.

Dealing more particularly with my invention, the coating roll 3 usually deposits more coating material on web 1w than is necessary or desirable on the finished sheet. The removal of this excess material assists materially in accomplishing the first two objectives previously mentioned, namely, smoothing off or leveling of any high or thick portions of the coating material, and filling in any thin portion or portions of the traveling web which were not sufficiently covered. By having an excess of coating material these two objectives can be more readily accomplished but nevertheless this excess coating material must be removed entirely away from the sheet and preferably delivered back to tank 4 for reuse. Any and all excess material which is removed from the sheet by the air jet is first collected in the expansion pans 13 and 14 from which pans it can be removed for reuse.

In removing this excess material from the web 1w by any of the present methods, and particularly with the air jet method, it is difficult to get the removed material completely away from the parts of the machine adjacent to the roll 5 and the traveling web 1w, and particularly away from parts immediately adjacent to the air jet opening 10.

The velocity of air from jet 10 which smooths and removes the excess coating material is relatively high and this velocity tends to break up the liquid of the coating material into more or less fine drops of vapor, which in turn being suspended in the air from the jet travel with this air until its velocity is very much dispersed. The purpose of the expansion pans 13 and 14 is to provide space where this air velocity can be reduced, and the excess coating material traveling with the air allowed to drop into the pans. However, the allowable space for these pans is limited and there is a tendency for the air to follow the edge of the pan downward toward the roll 5 and back upwards and under the box 9 resulting in precipitation of coating material on the under side at point 12 said precipitated material gradually increasing in mass toward the roll 5 over which the coated paper is passing.

This mass of partially solidified coating material which lodges on the bottom of box 9 is not uniform but projects more or less at scattered points until the mass may be increased to an extent where it partially or wholly obstructs the jet of air coming from the jet or nozzle 10, under which condition an excess of coating material is

left on the sheet at that point. This mass of deposited coating material thus deposited along the bottom of box 9 may be built up until it actually touches the traveling sheet, and scraping off the coating material causes a deficiency of coating at that point and a thin streak or mark lengthwise of the web.

I have found a method whereby not only is there a minimum of coating material deposited on the bottom of the box 9, but such material as may come in contact with the box is immediately removed before it can build up to cause trouble.

To accomplish my purpose I provide an auxiliary air jet 15 located on the bottom of box 9. My preferred form of construction is to provide on the bottom of box 9 a plate 16. On the upper side of and between the plate 16 and the box 9 is a distributing air chamber 18. Connecting to this air chamber 18 are a plurality of openings or holes 19 which connect with the interior of box 9 and are supplied with air pressure from the interior of this box furnished through pipe 11. The air which is under pressure in the interior of box 9 passes through openings or holes 19 into the distribution chamber 18 and from this chamber through a narrow slot or opening 15 which distributes this air under pressure on the under surface of box 9 and directly across that portion of 12 where the coating material tends to accumulate.

In order to effect a uniform and also an adjustable distribution of this air through slot or opening 15 I provide a plurality of air valves 17 which are effective to adjust the amount of air delivered from box 9. The distribution of air through slot 15 can be adjusted as may be desirable or necessary to effect a complete elimination of a coating deposit at point 12 or at any position on the under side of box 9.

By properly proportioning the amount of air and size of opening 15, the eddy currents of air caused by the impinging of air through slot 10 against the web 1w on roll 5 can be largely eliminated or removed insofar as this eddy current of air tends to carry the coating material back up and on to the under side of box 9 at point 12. By providing this auxiliary air jet 15 directly along under surface of box 9 I not only prevent any accumulation of coating material on any portion of the box and particularly at point 12 but assist in the operation of air through distributing slot 18 by eliminating eddy currents below this slot and effecting a more thorough and uniform removal of any surplus coating material on the web 1w.

The valves 17 not only serve to adjust the distribution of the air at various points in the width of the web but also to adjust the amount of air to be in proper proportion or ratio with the air impinged on the sheet through slot 10.

As an optional method of supplying this auxiliary air jet to the under surface of box 9 I may provide a slotted pipe or tube as illustrated in Fig. 6. This shows a pipe 20 with a slot or opening 21 extending the entire width of the under surface of the box 9. To this pipe 20 is supplied air under pressure controlled by valve 22. This valve 22 serves to properly proportion the amount of air delivered through slot 21 and in proper ratio with the air delivered through slot 10 from the main air box 9.

This optional arrangement however, does not have the added feature of being able to adjust the amount of air supplied to the auxiliary slots at various points in the width of the web 1w.

My invention however, is not limited to either of the particular arrangements illustrated in Figs. 3 and 6 or to the specific use of a primary air jet for distributing uniformly a coating material over a web or sheet or this means for removing surplus material.

The foregoing description and illustrations used therewith is simply illustrative of my preferred method of application and apparatus therefor.

Having described my invention, what I desire to claim by Letters Patent, is:

1. An apparatus for coating paper comprising means for applying a coating material to a traveling web, gas blast means for smoothing said applied material and effecting a removal of any surplus material, and auxiliary gas blast means for effecting complete removal of any surplus coating material deposited on said first mentioned gas blast means.

2. An apparatus for coating paper, comprising means for moving a web of paper, means for applying a coating to said moving web, means for impinging a jet of air under pressure on said moving web and the coating thereon and gas blast means for preventing surplus coating material removed from the traveling web by air pressure from accumulating on parts of said jet impinging means adjacent to said traveling web.

3. An apparatus for coating paper comprising a means for applying a fluid coating to a moving web, means comprising an air jet for distributing said coating over said web and means comprising an auxiliary air jet operating in conjunction with the first mentioned jet for effecting more even distribution of the coating material on the web and an effective removal of the surplus coating material deposited on said first mentioned air jet means.

4. An apparatus for coating paper comprising means for applying a fluid coating to a moving web, gas blast means for distributing said coating over the surface of the moving web, means operating in conjunction with the before mentioned distributing means for effecting a more even distribution of the coating material on the web and a more effective removal of the surplus coating material from adjacent parts of said first mentioned distributing means and means for adjusting its effective action.

5. An apparatus for coating a traveling web, comprising means for applying a coating to said traveling web, means comprising an air jet for distributing said coating over said web, means comprising an auxiliary jet operating in conjunction with said first mentioned air jet for effecting a more even distribution of the coating material on the web, and a more effective removal of the surplus coating material, and means for adjusting the effective action of the auxiliary air jet relative to the first mentioned air jet.

6. The method of coating paper comprising the application of a coating material in fluid suspension to a moving web, the subjection of said moving coated web to a jet of air for effecting smoothing of the coating material and partial removal of any surplus coating material, and the subjection of said moving coated web and adjacent parts to a second jet of air for completing the removal of said surplus coating material from adjacent parts from which it may be redeposited back on the web.

7. An apparatus for coating paper comprising means for applying a coating material to a traveling web, means for impinging a jet of air on said moving web to smooth said applied material and effect a partial removal of surplus material, and auxiliary means for impinging a second jet of air on said moving web to complete the removal of surplus coating material already partially removed by said first jet, said auxiliary means including a nozzle positioned to direct its jet of air across portions of the apparatus adjacent the traveling web, whereby to maintain said portions free of accumulation of coating material.

8. An apparatus for coating paper comprising means for applying a coating material to a traveling web, means for smoothing said applied material and effecting a partial removal of surplus material from said web, auxiliary means for effecting complete removal of any surplus coating material already partially removed by said smoothing means, and deposited on said smoothing means, and means for adjusting said auxiliary means relative to said smoothing means.

DONALD R. MACDONALD. 50
